UNITED STATES PATENT OFFICE.

PHILLIP JACOB DREHER, OF TOLEDO, OHIO.

STOP MEANS FOR AUTOMATIC TYPE-WRITERS, &c.

1,149,561.

Specification of Letters Patent. Patented Aug. 10, 1915.

Original application filed August 29, 1911, Serial No. 646,661. Divided and this application filed February 16, 1912. Serial No. 677,935.

To all whom it may concern:

Be it known that I, PHILLIP JACOB DREHER, a citizen of the United States, and a resident of Toledo, in the county of Lucas and State 5 of Ohio, have invented a certain new and useful Stop Means for Automatic Type-Writers, &c.; and I do hereby declare the following to be a full, clear, and exact description of the invention, such as will enable others skilled in the art to which it appertains to make and use the same, reference being had to the accompanying drawings, and to the characters of reference 10 marked thereon, which form a part of this specification.

My invention relates particularly to automatically operated typewriters, but is not restricted to such use as it may be used in any connection for which it is applicable. 20 The primary object of my invention is the provision in combination with the drive means of a typewriter of means which is automatically operable to stop the driving means upon the removal of the last sheet 25 of paper or the like from the holding table therefor, thus enhancing the practicability of apparatus of this class.

The invention is fully described in the following specification, and while, in its 30 broader aspect, it is capable of embodiment in numerous forms, a preferred embodiment thereof is illustrated in the accompanying drawings, in which,—

Figure 1 is a side elevation of the invention in association with the sheet carrying table of a sheet feeding means for typewriters, and Fig. 2 is an enlarged sectional detail of one of the pneumatic units.

This application is a division of the application filed by me on August 29, 1911, 40 Serial No. 646,661.

Referring to the drawings, 1 designates a typewriter desk or other suitable part with which my invention may be associated, 2 a typewriter mounted thereon, and 3 the frame of a sheet feeding mechanism which is carried by the typewriter carriage 4 for movements therewith and has the sheet carrying table 5 rising on an incline from the 50 forward end portion thereof, as shown.

The mechanism which is shown in the present instance for successively feeding sheets to the platen-roll is the same as that described in my said former application 55 Serial No. 646,661. This mechanism com-

prises one or more pivotal arms 6, which carry at their free or swinging ends a hollow shaft provided with laterally projecting sheet picking-up mouth-pieces 7, which are in communication through a tube 8 with a suction device 9. A crank arm 10 projects downward from the mouth-piece carrying shaft and has its lower end in slotted pivotal connection with a push-bar 11 that is normally held at the limit of its rearward movement by the action of a spring 12 thereon.

The means employed for imparting properly timed rearward movements to the bar 11 as the feeding of the sheets to the typewriter platen may require is shown as being effected by the movement in one direction of a striker-lever 13, which is fulcrumed, as at 14, and has its upper end disposed in position to have contact with the rear end of the push bar 11 and impart longitudinal movements thereto when oscillated in one direction, or from normal position. The lower end of the lever 13 is engaged with the movable part of a bellows or pump 15 whereby a collapsing of such bellows imparts bar striking movements to the lever. This bellows has communication through a pipe 16 with the suction device 9, and its collapsing movements are controlled by the movement of a perforation in the control sheet 17 into register with a passage in the tracker 18, which passage is in communication with the bellows, as through a tube 19. A bellows or pump 20 which is also controlled from the tracker 18 operates a valve 21 to open and close communication between the suction means 9 and mouth pieces 7, as it may be desired to pick up a sheet by the mouth-pieces or release the same.

The suction device 9 is shown in the present instance as being operated by a belt 22 leading from an electric motor 23, which motor is shown in the present instance as having a switch in circuit therewith which comprises the fixed and movable contact parts 24 and 25, respectively.

In carrying out the feature of my present invention the movable switch part 25 is attached to the movable part of a bellows or pump 26, which is suitably carried within the desk, as by a bracket 27, and has its exhaust tube 28 communicating with the exhaust pipe 16, and its air inlet tube 29 leading thereto from an opening 30 in the bot-

tom of the sheet carrying table 5. The inlet end of the opening 30 is disposed in position to be covered by a sheet *a* when resting upon the bottom of the table 5, and upon 5 the raising of the last sheet from the table the opening 30 will be uncovered to the atmosphere to permit a circulation of air through the bellows 26 to the suction means, and a consequent collapsing of the bellows 10 by suction action, as is well understood in the art. Upon a collapsing of the bellows 26 in this manner the movable switch part 25 is thrown to open position, thus stopping the motor and operation of the suction device 9, or any other automatically operated 15 part of the typewriter to which the motor may be attached.

Numerous forms of bellows or pneumatic units 20 and 26 are on the market, and it will 20 be sufficient for an understanding of the operation of the invention to describe one form only thereof, which is shown in detail in Fig. 2. In these bellows, 31 designates the body or stationary part, and 31' the interior of the bellows proper. The body 31 is provided with a chamber 32, which has communication through a passage 33 with the suction pipe 16 and has communication 25 through a passage 34 with the interior 31' of the bellows. A diaphragm 35 is disposed in the chamber 32 and divides it into two compartments, one of which has communication with both passages 33 and 34, while the other has communication through a passage 30 36 with the tube 29 leading from the opening 30 in the sheet carrying table 5. A disk-valve 37 is disposed in the passage 34, and has its stem projected into the chamber 32 and attached to the diaphragm 35. When the 40 valve is raised by the suction action thereon from within the chamber 32 it closes the communication between such chamber and the passage 34, and when lowered, due to atmospheric pressure in the passage 36 upon the diaphragm 35, it is lowered and opens 45 the communication between the chamber 32 and passage 34 to the bellows and closes the opening 38 from the passage 34 to the atmosphere. It is thus apparent that when 50 the opening 30 in the sheet feeding table is closed by a sheet *a* the suction action within the chamber 32 will move the valve 37 to close the communication between the suction means and the interior of the bellows and 55 open the communication between the atmosphere and the bellows, and that upon an uncovering of the opening 30 the atmospheric pressure, which then rushes into the passage, acts upon the diaphragm 35 and effects a 60 movement of the valve 37 to open communication between the suction means and the interior of the bellows so that a sudden collapsing of the bellows is effected. A small bleed-opening 39 is provided between the 65 passage 36 and the suction chamber 32 so

that any air remaining in the passage 36 after a closing of the opening 30 will be slowly drawn therefrom to relieve the pressure on the side of the diaphragm 35 opposed to the valve.

It is thus apparent that I have provided 70 simple and efficient means for effecting a positive stopping of the actuating means of the typewriter operating parts, as in the present instance the sheet feeding means thereof, upon a removal of the last sheet *a* from the table 5. It is also evident that the suction passage 16, suction means 9, bellows 26 and passage 29 form a pneumatic system 75 that is rendered operative by a running of the motor or other suitable actuating mechanism 23, and that a change of pressure in the passage 29 renders the bellows 26 operable.

I wish it understood that my invention is 80 not limited to use in connection with any particular operating device, or any specific construction or arrangement of the parts except in so far as such limitations are specified in the claims.

Having thus described my invention, what 85 I claim as new, and desire to secure by Letters Patent, is,

1. In combination, an electro-magnetically operated means, a switch in circuit 90 with said means, a sheet holding table having an opening in its bottom adapted to be covered by a sheet carried thereby, and means pneumatically operable to open said switch upon the removal of the last sheet of 95 a pile from over said opening.

2. In combination, an electric motor, a switch in circuit with said motor, a sheet holding table having an opening in its bottom adapted to be covered by a sheet carried thereby, and means pneumatically operable to open said switch upon the removal 100 of the last sheet of a pile from over said opening.

3. In combination, an electric motor, a switch in circuit with said motor, a controlling means, a sheet holding table having a fluid inlet, a suction apparatus in communication with said inlet through said controlling means, said inlet adapted to be 110 closed by sheets placed on the table over the inlet and opened by removal of the last sheet, said controlling means being operated to move said switch to open position by a change of pressure in the communication 115 between said suction apparatus and inlet upon an opening of said inlet.

4. The combination with a sheet holding 120 table having an air inlet passage therein and mechanism operable to intermittently feed sheets from said table, of electric means 125 operable to actuate said mechanism, a switch in circuit with said means, and means which is pneumatically operable to open said switch when the air inlet passage in the 130

table is uncovered to the atmosphere by the removal of the last sheet of a pile from over the same.

5. The combination with a sheet holding table having an opening in its bottom adapted to be covered by a sheet carried thereby, electrically operated mechanism for delivering sheets from said table, and pneumatically controlled means in connection with 10 said opening and operable to stop the operation of said electrically operated mechanism upon the removal of the last sheet from over said opening.

6. The combination with a printing apparatus, and operating means therefor, of an electric motor for actuating said means, an electric switch in circuit with said motor, a table for holding a pile of sheets and having an opening covered by sheets thereon, 20 and means which is pneumatically operable to effect an opening of said switch upon the

uncovering of said opening by the removal of the last sheet of the pile from said table.

7. In combination, a sheet holding table from which sheets are fed, said table having 25 an opening therein closed by a sheet thereon, a motor, a switch operable to stop the running of said motor, a bellows attached to said switch, said bellows having communication with said table opening, and means 30 operable to create a suction through said bellows to cause a movement of said switch to stop the motor when said sheet covering said table opening has been removed therefrom.

In testimony whereof, I have hereunto signed my name to this specification in the presence of two subscribing witnesses.

PHILLIP JACOB DREHER.
